Primary Examiner—Robert M. Spear*Assistant Examiner*—Mary Ann Calabrese(74) *Attorney, Agent, or Firm*—Weingram & Associates, PC(57) **CLAIM**

I claim the ornamental design for circular pillow, as shown and described.

DESCRIPTION

FIG. 1 is a top perspective view of the present invention.

FIG. 2 is a top plan view of FIG. 1.

FIG. 3 is a bottom plan view of FIG. 1.

FIG. 4 is a right elevational view, which is a mirror image of the left elevational view of FIG. 1; and,

FIG. 5 is a front elevational view, which is a mirror image of the rear elevational view of FIG. 1.
